UNITED STATES PATENT OFFICE.

OTTO ROSENSTEIN, OF SAN FRANCISCO, CALIFORNIA, ASSIGNOR TO K. SCHROER, OF BERKELEY, CALIFORNIA.

DESIGN FOR A PRESERVE JAR.

Application filed August 23, 1924. Serial No. 10,542. Term of patent 7 years.

To all whom it may concern:

Be it known that I, OTTO ROSENSTEIN, design a citizen of the United States, residing in city and county of San Francisco, State of California, have invented a new, original, and ornamental Design for Preserve Jars, reference being had to the accompanying drawing, forming part thereof.

Fig. 1 is an elevation showing my new

Fig. 2 is a sectional view taken on line 2—2 of Fig. 1.

I claim:

The ornamental design for a preserve jar, of which the following is a specification, as shown.

OTTO ROSENSTEIN.
